CASE-SHIFTING MECHANISM.

1,388,616.

Specification of Letters Patent. Patented Aug. 23, 1921.

Application filed February 14, 1920. Serial No. 358,593.

To all whom it may concern:

Be it known that I, CHARLES SPIRO, citizen of the United States, residing at New York, in the county of New York and State 5 of New York, have invented certain new and useful Improvements in Case-Shifting Mechanism, of which the following is a specification.

This invention relates to a case shift mechanism for typewriters and particularly to 10 a construction wherein the platen is shifted for upper case writing and the ribbon carrier simultaneously shifted to maintain its relative position to the printing point upon 15 the platen.

The invention has for an object to provide 20 a novel and improved construction of shifting mechanism comprising a rock-shaft having an arm disposed to effect a downward draft upon the shift rail for a platen, and 25 an opposite arm connected to effect a simultaneous upward movement of the ribbon carrier.

A further object of the invention is to 30 provide an improved construction of case-shifted ribbon carrier pivotally mounted and tensioned toward the printing face of the platen so that the ribbon lies immediately adjacent thereto and resistance to the type-bar printing movement by the ribbon is practically eliminated.

Another object of the invention is to present a novel construction and arrangement 35 of parts and their connections whereby the case-shifting of the platen and ribbon may be effected without altering their normal operation through the actuating means for effecting vibration of the ribbon and the extent of such vibration for color shifting.

40 Other and further objects and advantages of the invention will be hereinafter set forth and the novel features thereof defined by the appended claims.

In the drawings,—

45 Figure 1 is a vertical section showing the invention applied;

Fig. 2 a skeletonized plan of the operative parts,

Fig. 3 a detail front elevation of the line 50 indicator and ribbon carrier supported thereby, and

Fig. 4 is a detail sectional view on line 4—4 of Fig. 3.

Like numerals refer to like parts in the 55 several figures of the drawings.

The numeral 10 designates the frame of a

typewriting machine, which may be of any desired construction or configuration, and is provided with the usual top plate 11 and segment 12 for supporting the type bars 13. 60 In the illustration of the invention only such portions of the typewriter frame are shown as is necessary to locate the respective parts. Mounted upon the top plate is the carriage 14 of any ordinary construction, 65 which is driven by a gear 15 from the spring drum 16 upon the top plate coöperating with a rack 17 upon the carriage. This carriage also supports the platen 18, which is removably mounted in open seats 19 70 formed in the shifting side plates 20. These plates are pivotally connected at 21 with the shift arms 22, which are mounted upon the cross-rod 23 pivoted in the fixed side plates 24 of the carriage. The shift plates 20 are 75 also pivoted at 25 to an equalizing link 26, which is pivoted in the fixed side plates 24 at its rear end 27, and is restored to normal position by a spring 28, surrounding the pivot 27, and bearing upon the link as shown 80 in Fig. 1. The opposite shift arms 22 are connected by a cross-rail 29 at the rear.

For the purpose of shifting this rail downward and raising the platen for upper case work, through connection just described, a shift rod 30 is mounted in the frame for vertical sliding movement and provided at its upper end with an arm 31 carrying a contact roller 32 which rides upon the upper face of the rail 29. In order to 90 disconnect this roller from the rail, if it be desired to remove the carriage, the arm 31 is pivotally mounted at 33 upon the rod 30, and the tail 34 of the arm extends beyond the rod and is held in normal position by a 95 spring 35, while the upward movement of the arm is limited by a stop 36 at the opposite side of the rod from said spring. This construction permits the traveling wheel 32 to be removed from the shift rail and retained in its removed position while, when in operative position, it is securely held so that the draft upon the rail is in direct line from the shift rod.

Motion is transmitted to the vertical shift 105 rod 30 by means of a rock-shaft 40 pivoted at its opposite ends 41 in the sides of the frame 10. This rock-shaft is formed with a rearwardly projecting arm 42 pivotally connected at 43 with the lower end of the 110 shift rod 30, and has also an oppositely extending arm 44, provided with a bifurcated

or slotted free end 45, which is connected to a slide member 46 carrying the line indicator arms 47. The rock-shaft is actuated by a key-lever 48 of any ordinary form, which is 5 pivotally mounted at 49 upon a fulcrum 50 at the rear of the machine frame, and is normally held in raised position by means of a tension spring 51 extending from the lever to a supporting hook 52 upon the frame. 10 The lever 48 has secured thereto a vertical arm 53 provided with a lateral lug 54 disposed to contact with a depending projection 55 from the rock-shaft 40. This projection is formed with a curved face 56, so 15 as to secure a rolling contact between the lug 54 and part 55, thus greatly reducing the friction and providing for a proper rolling movement of the parts upon each other, owing to different arcs of travel. 20 The slide member 46 which carries the indicator arms 47 is provided with ears 57 which embrace a slide block 58, mounted upon a cross-rail 59 of the machine, so as to insure movement in a true vertical path. At 25 the lower portion of the slide a connecting bar 59' is provided, which enters the slotted end of the rock-arm 44, before described, and thus receives motion therefrom. The opposite sides of the slide 46 are formed with 30 depending arms 60 disposed at substantially a right angle to the body of the slide and provided at their lower ends with pivotal mountings 61 for the arms of the line indicator. 35 At the upper ends of the arms 47, the body 62 of the line indicator forms a support for the ribbon carrier 63. This carrier at its upper end has the usual ribbon fingers 64, and at its lower end the connecting eye 65 40 for the vibrating means to be hereinafter described. The ribbon carrier is held against lateral displacement upon the body 62 of the line indicator by means of lugs 66 therefrom extending over the carrier as shown in Fig. 45 3, and the upper end of the body 62 is provided at each side of the carrier with the usual indications 67 to coöperate with the platen at its printing face. The line indicator and ribbon carrier supported thereby 50 are normally tensioned toward the printing face of the platen 18 by any desired means, one form of which is herein shown, and comprises a spring 68 secured to the body of the indicator at 69 and bearing at its free end 55 against the inner face of the segment 12. The movement of the indicator and carrier toward the face of the platen is limited by a keeper 70 secured to the inner face of the segment, but this limiting of the contact of 60 the indicator with the platen is so disposed as to permit a constant contact between the upper end of the indicator and the printing face of the platen which holds the ribbon immediately adjacent thereto under all conditions. If the platen be removed from the 65 carriage, the keeper prevents further inward movement of the indicator. This construction provides an important improvement in both the type bar contact with the platen and the ribbon movement, as the ribbon is 70 not drawn or tensioned by the type bar at the instant of printing, and the resistance to the type-bar movement at this time is practically eliminated. The construction of the indicator for supporting the ribbon 71 provides for its position immediately adjacent the printing face of the platen, but without actual contact therewith, and thus avoids smutting or soiling of the paper. The ribbon mounting also provides for an equal and 75 light contact with the line indicator whenever a number of sheets are fed to the platen, as it yields away therefrom for the distance equivalent to the body of paper carried upon the face of the platen. 80 Extending from the connecting eye 65 of the ribbon guide 63 is a depending link 72, which is connected at its lower end with a vibrator lever 73, by means of a pivotal connection 74. This lever is suitably pivoted at 75 to arms 76, extending from the slide 46. 85 For the purpose of actuating this vibrator lever, a rearwardly extending arm 77 is provided upon the universal bail 78, which is mounted in the segment 12 and actuated 90 by a shoulder 79 upon the type bars 13. These type bars are mounted upon a pivot 80 in the usual manner and provided with a slot 81 to receive an actuating pin 82 carried by the sub-lever 83, which is pivoted at 84 100 in the cross-bar 59 of the frame. This connection secures an acceleration of the speed of the type bar and a reduction in the leverage as it approaches the printing point. The sub-lever 83 is provided with a short arm 105 85, which is pivotally connected to a depending link 86 pivoted at 87 upon a key lever 88 of the usual construction. This link connection provides for a direct downward draft upon the sub-lever and avoids the 110 friction of a rolling or sliding contact between the sub-lever and the key lever. While this type-bar action has been described herein, the novel features thereof are the subject of a separate application filed May 1, 1920, 115 Serial No. 362,248. 120 The universal bail 78 is provided at its inner end with a head 90, by which movement is imparted to the vertical arm 91 of the vibrator lever 73 and the ribbon carrier consequently vibrated upon the line indicator. For the purpose of varying the extent of this vibration so that the different paths upon the ribbon may be used, as in bichrome work, a color shifting plate 92 is slidably 125 mounted upon the arm 91 of the vibrator; and has the oppositely disposed engaging hooks 93 and 94 adapted to contact with the T-head 90 of the bail at different points from the axis of the vibrator lever, and thus 130

- vary the throw thereof. As the members before mentioned are case-shifted with the platen, it is necessary to provide a compensating connection between the color shift 5 plate 92 and its actuating means carried upon the frame of the machine. For this purpose a link 95 is pivotally connected at its opposite ends 96 and 97 to the slide 92 and a shift lever 98, respectively. This shift 10 lever is pivoted upon a frame at 99 and its lower end, engages a cam member 100 carried by the sliding rod 101, which extends to the keyboard of the machine and is there provided with the usual indicating lever 15 102 for shifting the same to different color positions. While the color shift mechanism has been herein described as a co-operating part, it is the subject of a separate application filed March 8, 1920, Serial No. 364,180.
- 20 In the operation of the invention, it will be seen that the depression of the shift key actuates the rock-shaft and the opposite arms thereon, resulting in a downward draft upon the shift rail connected to the platen, which 25 raises the latter for upper case work and simultaneously shifts upward the slide which carries both the ribbon guide and its supporting line finder, as well as the vibrator. This action bodily raises the ribbon in order 30 to maintain its relative position to the printing face of the platen during upper case work and permits the same relative vibration of the ribbon toward and from the printing point. The connection between the 35 shift key and the rock-shaft provides for a rolling movement of the parts upon each other, and also for the independent restoring of the key when the platen and ribbon mechanism are restored through the devices 40 for that purpose. The construction of the sliding shift bar provides a pivotal support for the line finder which, in turn, slidably supports the ribbon carrier, while the extended arms from this slide member provide 45 a pivotal support for the vibrator lever. This lever has a case-shifting connection by the elongated T-head from the universal bail, and the color shift device carried by the lever is also permitted to case- 50 shift through the compensating link with its actuating lever. The yielding support for the ribbon carrier which disposes it immediately adjacent the printing face of the platen prevents any movement of the ribbon 55 by the type bar toward the platen in the printing action, and thus eliminates the resistance to the final portion of the type stroke which, it will be understood, is a resilient movement of the type-bar, as usual 60 in this art. It has been found that with the ribbon spaced from the platen face, it is necessary to drag or force the ribbon inward for a distance before making the impression upon the paper carried by the platen. Such 65 action results in uneven impressions, as the resistance of the taut ribbon materially reduces the momentum of the type bar and increases the pressure required upon the key lever, in order to secure a clear and well-defined impression at the printing point. It 70 will be understood that in the use of the case-shifting mechanism, a suitable shift-lock may be provided, and as this is ordinary in the art, such construction has not been herein shown. 75
- The invention presents a simple, efficient and economically constructed mechanism for securing the simultaneous shifting of the ribbon carrier and platen, and while the specific construction of many of the parts 80 has been shown and described, the invention is not confined thereto, as will be defined by the following claims:
- What I claim is:
1. In a typewriter, a frame, a horizontal cross bar therein, a slide block carried by one face of said bar, a ribbon vibrating member carried by a support slidably mounted upon said block, and means for case shifting said support and member upon said bar. 85
  2. In a typewriter, a shiftable platen, a rock shaft provided with an arm, and a ribbon holding member having its lower portion mounted to slide upon a fixed support and directly connected by a lost motion connection to said arm to be case shifted thereby. 90
  3. In a typewriter, a shiftable platen, a rock shaft provided with an arm to shift said platen, an opposite arm upon said shaft, 95 a fixed support provided with a slide member, and a ribbon holding member mounted to slide thereon and directly connected to said opposite arm to be case shifted thereby. 100
  4. In a typewriter, a carriage provided with a case shifting platen, a fixed support provided with a slide member, a ribbon carrier slidably mounted thereon, a vibrator lever for the carrier mounted upon said slide member, means to jointly case shift said carrier and lever, and a universal bail having a head disposed in a plane parallel to the slide member to engage said lever and permit case shifting thereof. 105
  5. In a typewriter, a shiftable platen, a shift rail therefor, a shift rod engaging said rail, a rock shaft having an arm connected to said rod, an opposite arm upon said shaft, 110 a fixed support provided with a slide member, a vertically movable shift member mounted thereon and having a lost motion connection with said opposite arm, a line indicator pivotally supported upon said shift member, and a ribbon carrier supported upon said indicator. 115
  6. In a typewriter, a shiftable platen, a rock shaft having an arm connected to shift said platen, an opposite arm upon said shaft, 120 a vertically movable shift member directly connected to said opposite arm, a line indicator 125 supported upon said indicator, and a ribbon carrier supported upon said indicator. 130

cator pivotally supported upon said member, a ribbon carrier upon said indicator, a rearwardly extending arm from said shift member, and a vibrator lever pivoted upon said arm and connected to said ribbon carrier.

7. In a typewriter, a shiftable platen, a rock shaft having an arm connected to shift said platen, an opposite arm upon said shaft, 10 a vertically movable shift member directly connected to said opposite arm, a ribbon holder pivotally supported upon said member, a ribbon carrier upon said holder, a rearwardly extending arm from said shift member, a vibrator lever upon said arm connected to said carrier, and a spring interposed between said ribbon holder and a fixed part to force the holder toward said platen.

8. In a typewriter, a frame, a typebar action therein, a universal bail actuated by the typebars of said action, a vibrator lever having a case-shifting connection with said bail, a ribbon carrier actuated by said lever, a holding member for said carrier, a rock shaft 25 having an arm directly engaging said holding member, and a shift key connected to said shaft.

9. In a typewriter, the combination of a platen, means for case-shifting the same, a 30 simultaneously case shifted slide member, a ribbon supporting device pivoted upon said member, a ribbon carrier upon said device, a vibrator lever for said carrier mounted upon said slide member, and means for actuating said lever.

10. In a typewriter, the combination with a platen and means for shifting the same, of a shift key, a rock shaft actuated thereby, an arm from said shaft, a slide block mounted upon a fixed part, a slide member thereon directly actuated by said arm and having a rearwardly extending arm, a ribbon carrier, a support therefor pivoted upon said slide member, a vibrator lever pivoted upon said rearward arm and connected to said carrier, and means for actuating said vibrator.

11. In a typewriter, a frame, a case shifting unit comprising a slide member, a ribbon carrier supported thereby, a ribbon vibrator supported from said member at the rear thereof, means for actuating said vibrator, and means for shifting said slide member.

12. In a typewriter, the combination of a platen and means for shifting the same, a 55 slide block mounted upon a fixed part, a slide member disposed thereon and having a supporting arm, a ribbon carrier pivotally supported upon said member, a vibrator lever pivoted upon said supporting arm and connected to said carrier, means for actuating said lever, means for case-shifting said slide member, and a resilient member disposed to

force the ribbon carrier support toward the platen face.

13. In a typewriter, the combination of a platen and means for shifting the same, a slide block mounted upon a fixed part, a slide member disposed thereon and having a supporting arm, a ribbon carrier support pivoted upon said member, a vibrator lever pivoted upon said supporting arm, means for actuating said lever, means for case-shifting said slide member, a resilient member disposed to force said ribbon carrier support 70 toward the platen face, and a keeper to limit the travel of said support toward the platen.

14. In a typewriter, a platen, a ribbon carrier, and a support therefor normally yieldingly forced toward the printing face of said 80 platen whereby the ribbon is disposed immediately adjacent said face.

15. In a typewriter, a platen, a ribbon carrier, a support therefor normally yieldingly forced toward the printing face of said 85 platen whereby the ribbon is disposed immediately adjacent said face, and means for case-shifting said holder and carrier simultaneously with the shift of said platen.

16. In a typewriter, a platen, a ribbon carrier, a support therefor normally yieldingly forced toward the printing face of said 90 platen whereby the ribbon is disposed immediately adjacent said face, means for case-shifting said support and carrier simultaneously 95 with the shift of said platen; means for vibrating said carrier, and actuating means for said vibrator disposed to permit case shift movement of the latter.

17. In a typewriter, a frame, a slide block 100 carried by a fixed member thereof, a slide member mounted thereon and having arms at opposite sides, rearwardly extending parallel arms from said member, a vibrator lever carried by said parallel arms, a line indicator having depending portions from its body pivotally mounted upon the side arms of said slide, a ribbon carrier supported upon the body of said indicator, and means for case-shifting said slide member.

18. In a typewriter, a frame, a slide block carried by a fixed member thereof, a slide member mounted thereon and having arms at opposite sides, rearwardly extending parallel arms from said member, a vibrator lever 115 carried by said parallel arms, a line indicator having depending portions from its body pivotally mounted upon the side arms of said slide, a ribbon carrier supported upon the body of said indicator, a rock-shaft having an arm provided with an elongated slot and engaging said slide member and a shift-key lever disposed to actuate said rock-shaft.

In testimony whereof I affix my signature. 125
CHARLES SPIRO.
